UNITED STATES PATENT OFFICE.

EDGAR M. WALTON, OF KANSAS CITY, MISSOURI.

CEMENT SHINGLE STRUCTURE.

1,077,321.

Specification of Letters Patent.

Patented Nov. 4, 1913.

Application filed May 2, 1910. Serial No. 558,918.

To all whom it may concern:

Be it known that I, EDGAR M. WALTON, a citizen of the United States, residing at Kansas City, in the county of Jackson and State of Missouri, have invented certain new and useful Improvements in Cement Shingle Structures; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to cement roof or side-wall coverings, and more specifically, to a shingle structure wherein shingles resembling wooden shingles in appearance are molded in their final positions on the roof or side of a house.

It is the object of my invention to provide a roof which will not crack, is permanent, sightly, and fire-proof and is moreover inexpensive of construction.

The invention consists in the details of construction herein to be described, and illustrated in the accompanying drawing, in which:—

Figure I is a perspective view of a part of a roof, including a hip and a valley, constructed according to my invention. Fig. II is a plan view of portions of several courses of cement shingles, showing their arrangement. Fig. III is an enlarged vertical section of my cement shingles and the supporting sheathing. Fig. IV is an enlarged plan view of one of the metallic inserts around which a shingle is molded.

Referring more in detail to the parts:— In covering a wooden sheathed roof according to my invention, the operator is supplied with a number of sheet metal inserts, as foundations for the cement shingles.

A suitable insert, 1, is shown in Fig. IV, the same having semi-circular spacing ears 2 struck up from both sides of the insert 1 leaving similarly shaped perforations therein. Any form of "expanded" sheet metal

1, or "metal lath" as it is sometimes called, may be employed. The insert 1 is cut to nearly the size of the shingles, and if the roof has hips or valleys specially shaped inserts 1 are cut, having the contour of the shingles 3, 4, shown in Fig. I.

Beginning at the lower edge of the roof as usual, the operator fastens a course of inserts 1 to the sheathing 5 with staples that pass through openings in the inserts, as shown in Fig. IV, where 6 designates a 60 staple. One staple for each insert 1 will suffice. The wet cement is then spread upon the insert, and is molded into shingle form, filling all the interstices of the insert, and being tapered in thickness from end to end 65 as are wooden shingles. Grooves 7 are indented, in imitation of the cracks between wooden shingles. Suitable molding apparatus should be employed, and an apparatus expressly invented by me for that 70 purpose is described in a pending application for Letters Patent. Said apparatus consists of horizontally disposed bars having, attached thereto, a series of upwardly extending arms which taper in thickness. 75 Said arms form the divisions or grooves between adjacent shingles, and the bars mold the lower ends of the shingles. These mold members are temporarily secured to the roof or side of the house with nails. Having completed the first course, or as much thereof as desired, the operator lays a second course of inserts 1 directly thereover, breaking joints, and using the staples as before. He then molds an upper course of cement upon the 80 lower course of cement. The former upper course covers the cracks between the shingles of the latter lower course. The next series of inserts 1 is stapled into place above and overlapping the upper part of the shingles 85 already formed, and the cement applied as above described. It should be noted that, whereas in wooden shingling spaces are formed between shingles of adjacent courses, in this cement construction no such spaces 90 are formed, as the material is plastic instead of being already fixed in rigid plates. Thus the roof covering will be strong and solid.

When the sides of the roof have been covered as described, the operator molds a cap 100 piece 8 upon the ridge of the roof, in imitation of the "saddle boards" of wooden roofs. Continuous strips of the metallic insertion may be employed for these parts.

In covering hips and valleys, as at the 105 right and left in Fig. I, I prefer to mold angular shingles, as 3 and 4, which thus cover the hips and valleys in a waterproof manner, which can not be done with wooden shingles even when supplemented by tin- 110

work. The same molds used in forming the rectangular shingles, are used in forming the hip and valley shingles 3 and 4.

Each shingle will adhere only slightly to those beneath it, even without the use of intervening sheets of paper. Owing to this fact, the expansion or contraction of the material during changes of atmospheric temperature will not crack the material, (as would be the case with an integral mass) but the shingles will expand or contract individually, preserving their integrity.

Having thus described my invention, what I claim as new therein and desire to secure by Letters-Patent is:—

1. A house covering having sheathing, a course of metal reinforcing inserts loosely secured to said sheathing, said inserts having a covering of plastic cement divided with respect to the inserts, a second course of inserts loosely secured to the sheathing and overlapping the finished course of cement, and a layer of plastic cement applied to the second course of inserts and divided with respect to said inserts, the interstices

between the sheathing, the second course of inserts and the upper edge of the first course being filled with cement to form a shoulder, for the purpose set forth.

2. A house covering, comprising a sheathing, a course of metal reinforcing inserts spaced from and loosely secured to said sheathing, said inserts having a covering of plastic cement divided with respect to the inserts, a second course of inserts loosely secured to the sheathing and overlapping the finished course of cement, and a layer of plastic cement applied to the second course of inserts and divided with respect to said inserts, each division of said last named course of cement being formed with a shoulder on its under side for abutting the top of the lower course, for the purpose set forth.

In testimony whereof I affix my signature in presence of two witnesses.

EDGAR M. WALTON.
